UNITED STATES PATENT OFFICE.

ANDREW G. HOWERTON, OF MEMPHIS, TENNESSEE.

APPARATUS FOR TREATING PILES.

Application filed June 25, 1926. Serial No. 118,543.

This invention relates to an improved method of and apparatus for treating piles with creosote and has as its general object to provide means whereby such treatment may be effected more economically and in a more thorough manner than by the present methods and apparatuses.

It is well known that there is no necessity for creosoting the portions of piles which are driven into the ground or submerged in water and which portions are consequently not exposed to the atmosphere, and yet, so far as I am aware, every apparatus previously designed for this purpose is so constructed that the piles are creosoted throughout their entire length which, of course, means a considerable waste of creosote. Therefore, the present invention has as one of its objects to provide means whereby piles of any length may be treated with creosote for any desired predetermined portion of their length, so that the treatment of the piles may be confined to only such portions as require to be so treated, thereby effecting a great saving in creosote.

Another object of the invention is to provide, in apparatus for treating piles with creosote, means whereby the creosote may be recovered after the several steps of the process have been carried out, thus further economizing in the use of this substance.

A further object of the invention is to provide means whereby the piles to be treated may be first subjected to the action of steam under pressure so as to effect a desired swelling or expansion of the cells of the wood, means whereby the piles may then be subjected to vacuum to effect evacuation of the pores of the cells of the wood, and means whereby the piles may then be impregnated with creosote throughout such portions of their length as require such treatment, so that a thorough impregnation of the piles by the creosote is effected.

In the accompanying drawings:

Figure 1 is a view in side elevation of the apparatus embodying the invention, the pile containing cylinder being illustrated in horizontal position and in position to permit of the introduction of the piles thereinto, the said cylinder, in the said view, being shown in dotted lines in upright position and which position it will assume when the piles are being treated in accordance with the method of the invention.

Figure 2 is a top plan view of the apparatus.

Figure 3 is a horizontal sectional view on an enlarged scale through the pile-receiving cylinder of the apparatus.

Figure 4 is a vertical transverse sectional view taken substantially on the line 4—4 of Figure 3, looking in the direction indicated by the arrows.

Figure 5 is an enlarged horizontal sectional view taken substantially on the line 5—5 of Figure 4, looking in the direction indicated by the arrows.

Figure 6 is a horizontal sectional view in detail, taken substantially on the line 6—6 of Figure 3, looking in the direction indicated by the arrows.

Figure 7 is a view in elevation of the receiving end of the cylinder of the apparatus and illustrating the door for closing this end of the cylinder after the piles have been introduced thereinto.

Figure 8 is a detail vertical sectional view taken substantially on the line 8—8 of Figure 7, looking in the direction indicated by the arrows.

Figure 9 is a view in side elevation of a brake which constitutes a part of the apparatus.

Figure 10 is a schematic view of the apparatus.

An essential part of the apparatus embodying the invention is the chamber into which the piles to be treated are introduced, and this chamber, which is indicated in general by the numeral 1, comprises a cylinder 2 which is of sufficient diameter to accommodate trucks and a number of piles which are loaded thereon and is of a length preferably slightly greater than the longest piles which will be treated. This cylinder may be of heavy sheet iron or cast, and it is preferably reinforced throughout its length by an exterior trussed frame structure indicated by the numeral 3, which may be of any suitable construction and, therefore, need not be specifically described. At one end, the cylinder 2 is permanently closed by a head 4 and at its opposite end it is provided with a cylinder head 5 which will presently be specifically described and which is movable into and out of position to close the said end of the cylinder in a fluid-tight manner. The numeral 6 indicates two bevel gears which are secured in any suitable manner, as for 100 construction and, therefore, need not be specifically described. At one end, the cylinder 2 is permanently closed by a head 4 and at its opposite end it is provided with a cylinder head 5 which will presently be specifically described and which is movable into and out of position to close the said end of the cylinder in a fluid-tight manner. The numeral 6 indicates two bevel gears which are secured in any suitable manner, as for 105 construction and, therefore, need not be specifically described. At one end, the cylinder 2 is permanently closed by a head 4 and at its opposite end it is provided with a cylinder head 5 which will presently be specifically described and which is movable into and out of position to close the said end of the cylinder in a fluid-tight manner. The numeral 6 indicates two bevel gears which are secured in any suitable manner, as for 110 construction and, therefore, need not be specifically described.

example to a base plate 7, to the frame structure 3 at the opposite sides of the cylinder 2, and, in the embodiment of the invention shown in the drawings, trunnions 8 are either fixed in the hubs of the gears or formed integrally therewith and are mounted in suitable bearings 9 which are mounted upon pillow blocks 10 at the opposite sides of a pit 11 provided in a concrete or similar foundation 12 upon which the apparatus is erected. In this manner, the cylinder is mounted so that it may be caused to assume the horizontal position shown in full lines in Figure 1 of the drawings, or the vertical position shown in dotted lines in the said figure, and the purpose of thus mounting the cylinder will presently be made clear.

The pit 11 is of dimensions to accommodate the lower portion of the cylinder when the cylinder is swung to upright position, and the bottom of the pit and that wall thereof opposite which the closed end of the cylinder will move when the cylinder is swung from one position to another, are preferably of the arcuate form shown in Figure 1, and a rail 13 is laid upon the said bottom and the said wall of the pit and is arcuate and concentric to the trunnions 8, and serves to guide the closed end of the cylinder and likewise serves another purpose to be presently explained.

In the embodiment of the invention disclosed herein, the means provided for effecting adjustment of the cylinder about its axis of rotation includes a steam engine 14 of ordinary construction having the usual crank connection 15 with a shaft 16 carrying a gear 17 which meshes with a gear 18 upon a shaft 19 mounted upon the foundation above the pit, this portion of the foundation which is indicated by the numeral 20, being built up above the pit to support not only the engine 14 and the mechanism which will now be described, but also other units of the apparatus which will be hereinafter referred to in more detail. The gear 18 is adapted to be connected with the shaft 19 for rotation therewith through the medium of a conventional clutch 21 adapted to be manually operated so that the transmission of power to the shaft 19 can be effected at will, in the carrying out of the method of the invention. Beveled gears 22 are freely mounted upon the shaft 19 and clutches 23 are provided to permit of either gear being clutched with the shaft for rotation therewith. These gears 22 are in mesh with beveled gears 24 fixed at the upper ends of shafts 25 which are provided at their lower ends with fixed beveled gears 26 meshing with the respective gears 6. At this point it will be evident that when one of the clutches 23 is thrown to clutch the respective gear 22 with the shaft 19, rotary motion will be imparted to the corresponding shaft 25 and, through the medi-

um of the gear 6, the cylinder will be swung from its horizontal to its vertical position, as shown in Figure 1, and when the other clutch is thrown, the first mentioned clutch being idle, the cylinder will be reversely 70 swung. The numeral 27 indicates a steam boiler of ordinary construction, and steam is supplied from this boiler through a supply pipe 28, to the engine 14 and may be controlled by the ordinary throttle valve (not 75 shown) associated with such engines. As will presently be explained, the boiler serves also as a source of steam supply for other purposes.

As previously indicated, the piles to be 80 treated are introduced into the cylinder on trucks which are indicated in the drawings by the numeral 29 and which travel upon track rails 30 leading to and in alignment with the open end of the cylinder when the 85 cylinder is in horizontal position, as clearly shown in Figures 1 and 2 of the drawings, the piles being, of course, loaded upon the trucks at any place however remote from the apparatus and conveyed by the trucks to the 90 apparatus. While the construction of the trucks is immaterial so far as the general invention is concerned, they are preferably provided with pile-supporting and embracing frames 31 of the general arcuate form 95 shown in Figure 4 of the drawings so that a number of piles loaded onto the trucks will be arranged in a more or less rounded pile adapting the whole number to readily enter the cylinder. Chains 32 are preferably connected each to one end of the respective frame and jack hooks 33 are mounted at the other end of the frame and are selectively engageable with the links of the respective chains so that the piles may be securely 100 bound in their piled up arrangement. As before stated, the track rails 30 lead to the open end of the cylinder in the horizontal position of the latter, and similar rails 34 are laid upon longitudinal sills 35 supported 105 within the bottom of the cylinder 2. The piles are so loaded upon the trucks that when the trucks are rolled along the rails in introducing the piles into the cylinder, the piles will be presented butt end first to the 110 open end of the cylinder, this being the end of a pile which requires impregnation with creosote or other preservative agents. It will be understood at this point, that inasmuch as the method of the invention contemplates adjustment of the cylinder to a vertical position, the butt ends of the piles will be lowermost when the cylinder is upright, and in order that the trucks 29 may be held 115 to the rails 34 while the cylinder is being 120 adjusted or swung, the pile supporting frames 31 of the trucks are provided with laterally projecting guards 36 having upturned ends 37 engaging behind flanges 38 125 extending downwardly from guide rails 39 130

which are mounted upon the inner side of the cylinder 2 at the opposite sides thereof, as clearly shown in Figure 4, and these rails are so located, as are also the guards 36, as to prevent the wheels of the trucks leaving the rails 34 when the cylinder is adjusted to vertical position.

As will be observed by reference to Figure 3 of the drawings, the rails 34 within the cylinder 2 extend from the open end thereof to a point somewhat short of the closed cylinder head 4 and when the piles loaded upon the trucks 29, are introduced into the cylinder, the butt ends of the piles will engage a false bottom which is arranged within the cylinder and which is indicated in general by the numeral 40. This false bottom may be of any desired and suitable construction but preferably comprises I-beams 41 which are mounted horizontally within the cylinder 2 and extend across the interior of the same and are secured at their ends to the wall of the cylinder at opposite sides thereof, other beams 42 being arranged vertically within the cylinder and parallel to each other and intersecting the beams 41. Wooden beams or sills 43 are mounted by U-bolts 44 upon the beams 41 and are arranged in spaced parallel relation preferably in a vertical position, and it is against these beams that the butt ends of the piles engage. It will now be evident that when the cylinder is swung from horizontal to vertical position, the butt ends of the piles to be treated will rest against the false bottom structure and thus be supported in spaced relation to the head 4 of the cylinder.

In a manner to be presently explained, creosote or other preservative agent is to be introduced into the cylinder to impregnate the piles, and in order that the preservative agent may be heated, a steam coil 45 is arranged within the cylinder between the head 4 thereof and the false bottom 40, and one end of the coil is led through the side of the cylinder and has applied thereto a pressure valve 46, a supply pipe 47 being connected to the other end of the coil and led along the bottom of the cylinder interiorly thereof to a point adjacent the axis of rotation of the cylinder where the pipe is led laterally, as at 48, and upwardly and thence through the wall of the cylinder and beyond the frame structure 3 where there is connected to it a flexible high pressure hose 49 leading to the casing of a manually operable cut-off valve 50 to which casing there is also connected a supply pipe 51 leading from the steam boiler 27. Under conditions to be presently described, steam is likewise to be supplied to the interior of the cylinder, and for this purpose a steam pipe 52 is arranged in the bottom or lower side of the cylinder and extends longitudinally thereof from a point adjacent the axis of rotation of the

cylinder to substantially the open end thereof. This pipe is, at its intake end, led laterally as at 53 and through the side of the cylinder and has connected to it a high pressure flexible hose 54 which is connected at its other end to the casing of a manually operable cut-off valve 55 with which the steam supply pipe 51 is in communication. The valves 50 and 55 are supported in any suitable manner, as for example as shown in Figure 4 of the drawings, together with other valves to be presently described, and at this point it will be evident that by providing the flexible hose connections and arranging the valves substantially in alignment with the axis of rotation of the cylinder, as illustrated in Figures 2 and 4, there is no interference with the flow of steam when the cylinder is swingingly adjusted.

In order that creosote or other preservative fluid substance may be introduced into the cylinder 2 to impregnate the piles, a pipe 56 is laid longitudinally between the track rails 34 and has one end opening relatively close to the head 4 of the cylinder and its opposite end portion 57 turned laterally and extended through the wall of the cylinder, a flexible hose 58 being connected to the last mentioned end of the pipe and to the casing of a manually operable cut-off valve 59 arranged, for example beside the valve 50. A pipe 60 leads from the said valve 59 to an oil heating and storage tank mounted upon the foundation 20. The numeral 71 indicates an oil pump which may be operated by a steam turbine 72 supplied with steam through the pipe 28 or a branch thereof, and a pipe 73 is led from the oil pump 71 at one side thereof, and coupled to the pipe 60. A pipe 74 is led from the other side of the pump 71 to the top of the oil heating and storage tank 70, and a manually operable cut-off valve 75 is interposed in the said pipe. The coupling between the pipes 60 and the pipe 73 is indicated by the numeral 76 and it likewise serves to couple to the pipe 60 a pipe 77 which leads from the bottom or lower portion of the tank 70, a valve 78 being interposed in the length of the said pipe 77 between the tank and the coupling. The numeral 79 indicates a reservoir for the creosote or other preservative, and a pipe 80 is led from the reservoir to the coupling 76 and has a manually operable cut-off valve 81 interposed in its length.

The numeral 82 indicates a convertible air pressure and suction pump which may be operated by a steam turbine 83 supplied with steam from the pipe 28, and a pipe 84 is led from one side of the pump to the top of the oil heating and storage tank 70, a pipe 85 being led from the other side of the pump to one side of the casing of a manually operable cut-off valve 86 arranged, for example, between the valves 50 and 55. A flexible

hose 87 leads from the other side of the casting of the valve 86 and connects with the branch 88 of a combined air supply and suction pipe indicated by the numeral 89, the said branch of the pipe being led through the side of the cylinder between the pipes 48 and 53 and the pipe 89 being extended longitudinally between the track rails 34 from its said branch 88 to a point relatively close to the receiving end of the cylinder. In order that the swinging movement of the cylinder may be retarded as it approaches its horizontal and vertical positions, thereby avoiding injury to the mechanism, braking mechanism is preferably provided and comprises a brake drum 90 which is fixed upon one of the trunnions 8, and brake shoes 91 and 92 are arranged at opposite sides of the drum to have frictional contact therewith and are connected at their upper ends by a link 93. The lower end of the shoe 91 is pivotally connected to a pivot bolt 94 upon a supporting bracket 95 and a link 96 is pivotally connected at one end with the lower end of the brake shoe 92 and at its other end to a rocker 97 which is suspended from the said pivot bolt 94. A connecting rod 98 is connected to the lower end of the rocker and to the rod 99 of a piston 100 working in a brake cylinder 101 into one end of which is led an air supply pipe 102 leading from and constituting a branch of the pipe 85 which, as previously explained, is led from the air pump 82, it being evident, by reference to Figure 9 of the drawings, that when air is admitted to the cylinder 101 behind the piston 100, the shoes 91 and 92 will be caused to bind the drum 90 and thus retard the swinging movement of the cylinder.

In order that the receiving end of the cylinder may be closed in a fluid-tight manner, a closure head 103 is mounted by hinges 104 upon the trussed frame structure 3 at the open end of the cylinder and an annular seating member 105 is secured within the receiving end of the cylinder and supports a packing gasket 106 against which the inner side of the closure 103 is designed to seat when the closure is swung to closed position, as clearly shown in Figure 8 of the drawings. The closure is provided with a circumferential outstanding flange 107 having notches 108 in its periphery, and a circumscribing flange 109 is secured upon the exterior of the cylinder 2 at the said end thereof and is provided with similar notches 110. Bolts 111 are disposed within the notches 108 and 110 of the closure and flange 109 respectively, and are adapted to be tightened, after the closure has been swung to closed position, so as to securely seal the receiving end of the cylinder.

As previously stated, the piles are to be impregnated with creosote or other preservative for only a predetermined portion of

their length and in order that the level of the impregnating preservative may be readily ascertained, a plurality of gauges 112 are mounted upon that side of the cylinder which is uppermost when the cylinder is in horizontal position and are spaced different distances from the permanently closed end of the cylinder.

In order that the cylinder may be steadied in its movement about its supporting trunnions, an arcuate rail 113 is mounted upon the curved bottom of the pit 11, and spaced guides 114 are secured upon the outer side of the head 4 of the cylinder and straddle the said rail. The rail is preferably provided with a rack 115 with which meshes a gear 116 driven from an electric motor 117, so that this arrangement may be resorted to either alone or in conjunction with the cylinder adjusting means previously described, in effecting movement of the cylinder from one position to the other.

A safety valve 118 is placed in communication with that side of the cylinder which is uppermost when the cylinder is in horizontal position and at a point adjacent the receiving end thereof, as shown in Figure 1 of the drawings, so as to provide for escape of air under pressure if the pressure should reach an abnormal degree.

An air pressure gauge 119 is preferably associated with the air pump 82.

In order that water of condensation may be drained from the cylinder from time to time, as occasion may require, a drain valve 120 is arranged in that side of the cylinder which is the under side when the cylinder is in horizontal position.

In order that the supply of compressed air to the air brake cylinder 101 may be controlled, a manually operable cut-off valve 121 is interposed in the pipe 102.

The operation of the apparatus is as follows:

The piles to be treated are loaded onto the trucks 29 and the chains 32 are drawn over the loaded piles and engaged with the jack hooks 33 which are then operated to tighten the chains and the jacks are then locked. The cylinder at this time is in horizontal position and the trucks are moved along the rails 30 and the piles thus introduced into the cylinder until their butt ends engage the false bottom 40 of the cylinder, whereupon the closure 103 is swung to closed position and securely bolted in place. The valve 55 is now opened and steam is permitted to flow under pressure into the cylinder from the boiler 27 and through the pipe 52. The supply of steam is maintained for the required period of time and during the steaming operation the water of condensation may be drawn off by way of the drain valve 120. After the steaming step has been completed, the valve 55 is closed

and the valve 86 is open, the air pump 82 being set in operation to create a suction through the pipe 89 and thus create a partial vacuum within the cylinder 2. This vacuum is maintained and, in the meantime, the valve 50 is opened, thus admitting steam to the heating coil 45 to raise the same to the desired degree of temperature. Previously, oil has been delivered from the reservoir 79 by way of the pipe 80, to the heating and storage tank 70 through the medium of the oil pump 72, and the oil in the tank is heated to the required temperature. The cylinder is now adjusted to the vertical position and oil is introduced into the cylinder from the storage tank 70 by way of the pipe 74 either by opening the valves 59 and 78 and introducing air under pressure into the tank through the medium of the air pump 82, or by gravity, until the creosote or oil has reached the desired level, which may be determined by reference to the oil gauges 112. The supply of oil is then cut off and the valve 86 is opened and air under pressure is delivered into the upper end of the cylinder through the pipe 89 until the desired pressure is registered upon the gauge 119. In practice, the safety valve 118 will be set or adjusted to open at a higher pressure than the maximum desired pressure. In the meantime, the supply of steam to the heating coil 45 has been continued, and this supply and the supply of compressed air are maintained, oil being supplied to the cylinder to maintain the proper level until it is noted that the level remains constant without supplying more oil which, of course, indicates that the piles have become thoroughly impregnated with the preservative. The air pump and oil pump are then cut out of operation and the air in the cylinder is permitted to escape and the steam is turned off from the heating coil. The oil in the cylinder is then returned to the tank 70 either by introducing air under pressure into the upper end of the cylinder or through the operation of the oil pump. After all of the preservative has been discharged from the cylinder and returned to the tank 70, the cylinder is restored to its horizontal position, the closure 5 is opened, and the treated piles upon the trucks are withdrawn from the cylinder and the piles removed from the trucks.

Having thus described the invention, what I claim is:

1. In apparatus for impregnating piles with a preservative, a foundation therefor including a pit, a cylinder for receiving the piles to be impregnated, means supporting the cylinder for adjustment to horizontal and upright position, means for adjusting the cylinder, cooperative means on the cylinder and in the pit for guiding the cylinder during its movement of adjustment, means

for supplying preservative to the cylinder, means for supplying steam to the cylinder, and single means for selectively supplying air under pressure to the cylinder and exhausting air therefrom.

2. In apparatus for impregnating piles with a preservative, a cylinder for receiving the piles to be impregnated and closed at one end, means for closing the other end of the cylinder, a false bottom within the cylinder upon which the ends of the piles rest, means supporting the cylinder for adjustment to horizontal and upright position, means for adjusting the cylinder, means for supplying preservative to the cylinder, a steam heating coil in the cylinder between the closed end thereof and the false bottom, means for supplying steam to the said coil, means for supplying steam to the interior of the cylinder near the second mentioned end thereof, and single means for selectively supplying air under pressure to the cylinder and exhausting air therefrom.

3. In apparatus for impregnating piles with a preservative, a cylinder for receiving the piles to be impregnated, the cylinder being closed at one end, means for closing the other end of the cylinder, means supporting the cylinder between its ends for adjustment to horizontal and upright position, means for adjusting the cylinder, means for supplying preservative to the cylinder near the first mentioned end thereof, a false bottom within the cylinder spaced from the first mentioned end thereof, a steam heating coil within the cylinder between the false bottom and the said closed end of the cylinder, means for supplying steam to the said coil, means for supplying steam to the cylinder near the second mentioned end thereof, and single means for selectively supplying air under pressure to the cylinder and exhausting air therefrom.

4. In apparatus for impregnating piles with a preservative, a cylinder for receiving the piles to be impregnated, means supporting the cylinder for adjustment to horizontal and upright position, means for adjusting the cylinder, a container for preservative, means for conducting preservative from the container to the cylinder including a pipe opening into the cylinder near one end thereof, the said end of the cylinder being closed and being the lowermost end when the cylinder is upright, means for supplying steam to the cylinder near the other end thereof, means for closing the last mentioned end of the cylinder, and single means for selectively supplying air under pressure to the cylinder and exhausting air therefrom including a pipe communicating with the cylinder near the last mentioned end thereof.

5. In apparatus for impregnating piles with a preservative, a cylinder for receiving the piles to be impregnated, means support-

- ing the cylinder for adjustment to horizontal and upright position, means for adjusting the cylinder, the cylinder being closed at one end, means for closing the other end 5 of the cylinder, a false bottom within the cylinder spaced from the first mentioned end thereof, a steam heating coil within the cylinder between the said false bottom and the said first mentioned end of the cylinder, 10 means for supplying steam to the said coil, means for supplying steam to the interior of the cylinder including a steam conducting pipe opening into the cylinder near the second mentioned end thereof, and single means 15 for supplying air under pressure to the cylinder and for exhausting air therefrom including a pipe opening into the cylinder near the second mentioned end thereof.
6. In apparatus for impregnating piles 20 with a preservative, a cylinder for receiving the piles to be impregnated, means supporting the cylinder for adjustment to horizontal and upright position, means for adjusting the cylinder, the cylinder being closed 25 at one end, means for closing the other end

of the cylinder, a reservoir for the preservative, a pipe leading from the lower portion of the reservoir for conducting preservative therefrom, a pipe within the cylinder in communication with the first mentioned pipe 30 and opening into the cylinder near the closed end thereof, means for supplying air under pressure to the upper portion of the reservoir and single means communicating with the cylinder near the second mentioned end 35 thereof for supplying air under pressure thereto and exhausting air therefrom.

7. An apparatus for impregnating piles with a preservative, a cylinder, means for supporting the cylinder for adjustment to horizontal and upright position, rails extending longitudinally within the cylinder, 40 and upon which are guided the wheels of a truck supporting piles to be impregnated, and cooperative means carried by the truck 45 and cylinder for maintaining truck wheels upon the rails when the cylinder is upright.

In testimony whereof I affix my signature.

ANDREW G. HOWERTON. [L.S.]
